Des. 193,347
Patented Aug. 7, 1962

193,347

COMBINED TABLE, FLOWER STAND, AND LAMP

Irene Garcia, Dallas, Tex.
(1601 Stewart, Las Vegas, Nev.)

Filed Dec. 29, 1958, Ser. No. 53,967

Term of patent 7 years

(Cl. D33—14)

I claim:

The ornamental design for a combined table, flower stand, and lamp, as shown.
